[57] CLAIM

The ornamental design for a dispenser for air treating material, as shown.

DESCRIPTION

FIG. 1 is a top perspective view of a dispenser for air treating material showing my new design;

FIG. 2 is a cross sectional view taken on line 2—2 of FIG. 1;

FIG. 3 is a side elevational view showing the dispenser in an open position; and

FIG. 4 is a side elevational view showing the dispenser in a second open position.

FIG.1

FIG.2

FIG.3

FIG.4
